(57) **CLAIM**

The ornamental design for an automotive shift gate kit, as shown and described.

DESCRIPTION

FIG. 1 is a top perspective view of an automotive shift gate kit, showing my new design;

FIG. 2 is an exploded top perspective view thereof;

FIG. 3 is a bottom perspective view thereof;

FIG. 4 is a top plan view thereof;

FIG. 5 is a bottom plan view thereof;

FIG. 6 is a right-side elevational view thereof;

FIG. 7 is a left-side elevational view thereof;

FIG. 8 is a front elevational view thereof; and,

FIG. 9 is a rear elevational view thereof.

The broken lines showing a vehicle and gear shift knob in FIG. 1 depict environmental matter and form no part of the claimed design. The remaining broken lines depict portions of the automotive shift gate kit that form no part of the claimed design.

1 Claim, 7 Drawing Sheets
